UNITED STATES PATENT OFFICE.

CARL F. BRANDENBERGER, OF FORT MADISON, IOWA.

GRABBING TOOL.

Application filed January 19, 1926. Serial No. 82,329.

To all whom it may concern:

Be it known that I, CARL F. BRANDENBERGER, a citizen of the United States, residing at Fort Madison, in the county of Lee and State of Iowa, have invented a new and useful Grabbing Tool, of which the following is a specification.

This invention aims to provide a simple means whereby tools and the like may be fished out of a well.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:

Figure 1 shows in elevation, a device constructed in accordance with the invention;

Figure 2 is a section on the line 2—2 of Figure 1, parts remaining in elevation;

Figure 3 is a fragmental elevation showing the parts interengaged for the retraction of the sleeve;

Figure 4 is a cross section on the line 4—4 of Figure 3.

The device forming the subject matter of this application comprises a tubular body 1, which is a composite structure, the body including an upper member 2 and a lower member 3 connected by a coupling 4, the diameter of the lower member 3 being less than the diameter of the upper member 2, so that the upper end of the lower member 3 forms an internal shoulder 5 in the body 1. The lower member 3 of the body 1 has a depending trough-shaped arm 6 provided with a transverse projection or hook 7, the upper edge of which is laterally and downwardly inclined, as shown at 8. A reinforcing block 9 may be held by securing elements 10 in the upper end of the member 2 of the body 1, the aforesaid securing elements retaining, also, a hanger 11 of any desired sort, whereby the implement may be manipulated.

A plunger 12 is mounted closely but slid-

ably in the lower member 3 of the body 1 and is equipped at its upper end with an enlarged head 14 which is of such diameter that it cannot pass downwardly through the lower member 3 of the body 1, the head 14 being adapted to engage the shoulder 5, and the head being of such diameter that it can slide in the upper member 2 of the body 1. At its lower end, the plunger 12 is supplied with resiliently expandable grips 15, which are outwardly inclined, as shown at 16, the grips terminating at their lower ends in inwardly projecting claws 17.

A sleeve 18 of tubular form is mounted closely but slidably on the plunger 12 and has an upstanding trough-shaped arm 19 supplied with a transverse projection or hook 20, the lower edge of which is inclined, as indicated at 21, to cooperate with the inclination of the edge 8 of the hook 7 on the depending arm 6 of the lower member 3 of the body 1.

In practical operation, when the parts are arranged as shown in Figure 1, the sleeve 18 is slid downwardly, until its downward movement is stopped by the grips 15, the grips being expanded, as shown in Figure 1. The tool is lowered in the well, with the head 14 of the plunger 12 in engagement with the shoulder 5, the lower end of the arm 6 of the body 1 being spaced vertically, as a general statement, from the upper end of the arm 19 on the sleeve 8. The grips 15 are disposed about the object which is to be removed, and the body 1 is reciprocated vertically. Thereupon, the lower end of the arm 6 on the body 1 hammers on the upper end of the arm 19 on the sleeve 18, and forces the sleeve 18 downwardly on the plunger 12, the sleeve compressing the grips 15 about the object which is to be removed, and the grips assuming the position shown in Figure 2. When, if the operator desires to remove the object, he hauls up on the body 1, the plunger 12 and the object being raised, when the head 14 on the plunger comes into engagement with the shoulder 5 of the body 1.

It may happen that the object is so firmly lodged in the well that it cannot be removed after it has been engaged by the grips 15, and after the sleeve 18, which acts as a grip-compressor, has been driven down into the position shown in Figure 2. Under such circumstances, it is possible for the operator to release the sleeve 18 from

the grips 15, whereupon the implement may be pulled out of the well, without the object which the operator was trying to remove. In order to raise the sleeve 18 and release the grips, the body 1 is rotated, and then pulled upwardly, thus causing the projections or hooks 7 and 20 to engage with each other, as shown in Figure 3. When the sleeve 18 is raised the grips 15 are released, and when the head 14 on the plunger 12 comes into contact with the shoulder 5, the tool may be removed from the well independently of the lodged object.

What is claimed is:—

- 15 1. In a device of the class described, a plunger provided at its lower end with a compressible grip, a sleeve slidable on the plunger to compress and release the grip, a body rotatable on the plunger, and slidable 20 on the plunger to depress the sleeve and compress the grip, first interengaging ele-

ments on the body and the plunger and cooperating to secure a withdrawal of the plunger along with the body, and second interengaging elements on the body and the sleeve and cooperating to connect the sleeve with the body, for withdrawal, when the body is rotated.

2. A device of the class described, constructed as set forth in claim 1, and further characterized by the fact that the first interengaging elements embody a head and shoulder connection between the body and the plunger; the second interengaging elements comprising oppositely extended transverse projections on the body and on the sleeve.

In testimony that I claim the foregoing as my own, I have hereto affixed my signature.

CARL F. BRANDENBERGER.
